UNITED STATES PATENT OFFICE.

THOMAS V. ALLIS, OF MIDDLETOWN, OHIO.

METHOD OF HEATING SHEET-BARS.

1,046,933.

Specification of Letters Patent.

Patented Dec. 10, 1912.

Application filed November 28, 1911. Serial No. 662,860.

20 all whom it may concern:

Be it known that I, THOMAS V. ALLIS, a citizen of the United States, residing at Middletown, in the county of Butler and State of Ohio, have invented certain new and useful Improvements in Methods of Heating Sheet-Bars; and I do hereby declare the following to be a full, clear, and exact description of the invention, such as will enable others skilled in the art to which it appertains to make and use the same.

25 My invention relates to the art of heating sheet bars and it is an improvement whereby space is economized upon the hearth of a furnace adapted to heat the same; also to the manner of advancing them longitudinally along the hearth of a heating furnace.

In the drawings I have illustrated two types of furnaces that are adapted to the 30 carrying out of my invention.

Referring to the drawings:—Figure 1 is a horizontal section on line 1, 1 of Fig. 2 and Fig. 2 is a transverse vertical section on line 2, 2 of Fig. 1, also showing walls 35 and roof of furnace above said line. Fig.

3 is an enlarged plan view of the bars resting upon a broken portion of the upholding hearth guides. Fig. 4 is a cross section on line 4, 4 of Fig. 3. Fig. 5 is a plan view in longitudinal section on line d, d of Fig. 6 and shows a hearth designed for realizing my invention in connection with an ordinary pair heating furnace, the fire box and bridge wall common to such furnaces being shown. Fig. 40 6 is a vertical longitudinal section on line e, e of Fig. 5. Fig. 7 is a plan view in longitudinal section on line f, f of Fig. 8 and shows collections of sheet bars all upheld at one lateral inclination as may be arranged 45 in carrying out my invention. Fig. 8 is a vertical longitudinal section on line g, g of Fig. 7. Fig. 9 is a cross section of a modified form of hearth adapted for use in the ordinary pair heating furnace.

45 The continuous heating furnace illustrated in Figs. 1 to 4 inclusive is a type I may use in practising my invention. 1 is the heating chamber, 2 the furnace bottom and 3 the upholding hearth resting upon the bottom, and upon which the bars 4 are carried endwise and preferably in reverse angular abutment; 5 is a portal wall partitioning the heating chamber into two sections; it also divides the furnace otherwise into dual parts. 6 are bridge walls between said heating chamber and the mixing cham-

bers 7; 8 is a deflecting wall depending from the roof of the heating chamber; 9 are hollow walls which partition the heating chamber from the flues 10. Gas enters reservoirs 13 through downtake flues 14, and passes from thence through ports 15 into the mixing chambers 7. Air enters the hollow walls 9 through ports 16; becomes pre-heated to an extent in said hollow walls and passes down and through flues 17 to the air reservoirs 18, from thence it traverses the flues 18^a and ports 19 to said mixing chambers 7, wherein the gas and air commingle and in union ascend to the top of bridge walls 6, where combustion takes place; the flame reverberates under deflecting wall 8, passes over walls 9 and as a waste product of combustion escapes through flues 10 and 10^a to the open air through 75 chimneys shown in broken lines at 20. The waste products of combustion in their escape traverse flues 10^a, which being located directly under the hot air flues 17, aid in raising their temperature while in passage 80 to the mixing chambers.

In carrying out my new method for heating bars in connection with the furnace next above described, I proceed as follows:—The bars are charged at opening 11, 85 upon the upholding hearth 3, with their ends preferably crossed in reverse angular abutment to prevent them from over-riding while traversing the hearth; being forced from said opening through the heating 90 chamber 1, of the furnace, they pass under the arch in portal wall 5, to the discharge opening 12; from whence they are withdrawn and reduced to plates and sheets of varying gages, the bars having become properly heated while passing through the chamber.

The ordinary pair heating furnace with my improved hearth illustrated in Figs. 5 to 9 inclusive may also be advantageously 100 employed in realizing my invention. This furnace is provided with an upholding hearth formed with alternate parallel grooves and projections. The longitudinal side 22 is provided with a series of comparatively small doors that overlap each other at their sides, so that, while the large opening will be entirely closed when the doors are all down, all parts of the hearth are made accessible through said doors. The 105 doors are not shown in the drawings. Figs. 7 and 8 show collections of bars in process

of being heated while upheld at an angle upon said hearth.

In operating my invention in connection with the ordinary pair heating furnace last described, the bars are charged through the doors upon the upholding hearth at the same or reverse inclination to the perpendicular as shown in the drawings. When the bars are charged upon the upholding hearth at one inclination, I prefer to alternate the position of each charge rotatively, thus covering by a succeeding charge the angular upholding spaces left uncovered by the preceding charge, so that the bars all have hot supports to rest against. I accomplish this object in the following manner, for example:—Before the commencement of the week or working period, and in order to gain time, the hearth is charged with its full complement of bars early enough to bring them all to rolling temperature by the time the "turn" comes on. Following the withdrawal of the hot bars at one end of the hearth, others are charged to occupy the reverse angular hot spaces in the same grooves previously uncovered. This operation is continued until all the bars extending over the hearth have been withdrawn, at which time the metal at the opposite end of the chamber from which heated bars were last drawn is hot enough to roll; thus a rotative system of heating is established which continues throughout the working period.

My method of upholding bars at an angle during the process of heating economizes space upon the hearth of a furnace, as is well illustrated by the following example:—We will assume a heating chamber has an available width of twenty-four (24) inches, and the sheet bars to be heated are eight (8) inches wide. Three parallel rows of such bars horizontally laid with their longitudinal edges in contact will exactly fill this transverse dimension. Four parallel rows of the same bars may be located within said space if supported at an angle of about 45 degrees. The more acute the angle at which rows of bars are inclined to the perpendicular the greater the number of rows will be located within certain confines.

My method of upholding bars at a reverse angle during continuous or progressive heating permits the alternate covering and uncovering of space upon the hearth as shown in connection with the continuous heating furnace described, the bars are progressed continuously or intermittently upon the angular hot supports which are simultaneously covered and uncovered, thus the sup-

ports are subjected periodically to the direct heat of the furnace chamber.

I may secure increased economy of space in the heating chamber of a furnace by providing such a structure as is illustrated in Fig. 9. To recover heat in such a hearth I adopt a somewhat different method from that described in connection with Figs. 1 to 8. I leave the first groove 23, at the left of the figure vacant at the time the hearth is first charged with bars, which is after the hearth and all parts of the furnace have become thoroughly heated. When such bars are partially heated, those occupying the first groove at the right of the vacant groove 23 are turned over toward the left into said groove which leaves the first previously occupied groove unoccupied and exposed to the normal temperature of the furnace which it soon assimilates; the next row of bars at the right of this reheated groove is then turned toward the left into it, and as it is the hot top bar of the pair that comes in contact with the now reheated surface of the groove, such groove is robbed of but little heat. This operation is continued until all of the bars across the hearth have been turned into temporarily vacated and reheated grooves, at which time, the first bars turned are sufficiently hot to roll. After the hot bars occupying the first two grooves 23 at the left end of the hearth have been drawn, cold bars are charged into the second groove 23 which leaves the first groove again open and prepared for a duplication of the operation which is constantly repeated.

I claim:

1. The herein described method of heating sheet bars which consists in supporting them in grooves on a hearth within a furnace upon their lower longitudinal edge and a side; the bars being so placed that their adjacent ends cross each other; subjecting the bars to heat while thus disposed upon the hearth.

2. The herein described method of heating sheet bars which consists in supporting them in grooves on a hearth within a furnace upon their lower longitudinal edge and a side; the bars being so placed that their adjacent ends cross each other; moving the bars thus disposed over the hearth and at the same time subjecting them to heat.

In testimony whereof, I have signed my name to this specification in the presence of two subscribing witnesses.

THOMAS V. ALLIS.
